POULTRY HOUSING COMPLEX

Gerald L. Kitson, 9709 Belding Road,
Rockford, Mich. 49341

Filed June 1, 1971, Ser. No. 149,094

Term of patent 14 years

Int. Cl. D30—02

U.S. Cl. D30—1

FIG. 1 is a fragmentary top plan view of a poultry housing complex, showing my new design, portions being broken away and omitted to indicate indeterminate length;

FIG. 2 is a front elevational view to a reduced scale;

FIG. 3 is a fragmentary front elevational view to an enlarged scale; and

FIG. 4 is a fragmentary side elevational view to a reduced scale, portions being broken away and omitted to indicate indeterminate length.

I claim:

The ornamental design for poultry housing complex, as shown.
